US00D883226S

(12) **United States Design Patent** (10) Patent No.: **US D883,226 S**
Torres et al. (45) Date of Patent: ** May 5, 2020

(54) **PLUGGABLE MODULE**

(71) Applicant: **Methode Electronics, Inc.**, Chicago, IL (US)

(72) Inventors: **Luis Torres**, Schaumburg, IL (US); **Joseph Llorens**, Winfield, IL (US); **Alexandros Pirillis**, Skokie, IL (US); **Robert Skepnek**, Norridge, IL (US)

(73) Assignee: **Methode Electronics, Inc.**, Chicago, IL (US)

(**) Term: **15 Years**

(21) Appl. No.: **29/697,004**

(22) Filed: **Jul. 3, 2019**

CLAIM

The ornamental design for a pluggable module, as shown and described.

DESCRIPTION

FIG. 1 is an end view of the first end of the pluggable module of the present invention;

FIG. 2 is a right side elevation view of the pluggable module of the present invention;

FIG. 3 is a top plan view of the pluggable module of the present invention;

FIG. 4 is a left side elevation view of the pluggable module of the present invention;

FIG. 5 is a bottom plan view of the pluggable module of the present invention;

FIG. 6 is a perspective view of the pluggable module of the present invention; and,

FIG. 7 is an end view of the second end of the pluggable module of the present invention.

The broken lines in the drawings illustrate portions of the pluggable module that form no part of the claimed design.

1 Claim, 7 Drawing Sheets
